B. B. GOLDSMITH

MECHANICAL PENCIL

Filed April 22, 1921

UNITED STATES PATENT OFFICE.

BYRON B. GOLDSMITH, OF NEW YORK, N. Y.

MECHANICAL PENCIL.

Application filed April 22, 1921. Serial No. 463,711.

The present invention relates to an improvement in pencils of the kind known as "self-sharpening" or "ever-pointed" in which removable leads are inserted into a casing provided with mechanism for causing the lead to project more or less from the end, as it is worn away in use.

By means of my invention, the manufacture of pencils of this kind is very much simplified, as less parts are used than heretofore, and the assembling of the parts is so simple, that the cost of production is considerably reduced. An important feature of my invention which distinguishes it from other constructions, is that a lead tube is revolved in a case, and projects out of the front of it, and that portion which is within the case has all the attachments on its interior and exterior for feeding a lead, and that portion of the lead tube which projects out of the front of the case is not covered by any shell or holder, but in itself forms a finger piece to be grasped when the pencil is operated, as well as holding the lead rigid. In short, I construct a pencil with many less parts than usual.

My improved pencil is shown in a preferred embodiment in the accompanying drawings, wherein Figure 1 is a view partly in elevation and partly in longitudinal section, Figure 2 is a cross sectional view on the plane 2-2 in Figure 1, Figure 3 is a perspective view of the nut, Figure 4 is a similar view of the rotator shell and Figure 5 is a side elevation of the pusher for the lead.

The removable pencil lead 10 is accommodated within a lead tube 11 whose central bore fits and supports the lead, retaining it in place by friction in a well known manner. This lead tube is made of a solid rod centrally bored, which is threaded on its exterior surface, as shown at 12, and is provided with a longitudinal slot 13, clearly shown in Figure 2. A straight wire 14, fits into the bore of the tube 11, one end resting against the rear end of the lead 10 and its other end being bent so as to protrude through the slot 13, as shown at 15. This wire is the lead pusher, by whose immediate agency the lead is pressed forward and outward at will.

In order to operate the pusher 14 for this purpose a nut 16 is screwed onto the threads of the tube 11, and as it is revolved it advances along the tube, impinging upon the

bent tip 15, so as to press the pusher 14 and lead 10 forward.

The revolution of the nut 16 may be accomplished in a variety of ways, but I prefer to provide the nut with a depression 17 into which fits the longitudinal depression 18 in a rotator shell 19 which surrounds the nut, thus engaging with it in a manner to permit rotation of the nut by the rotator while allowing the nut to travel longitudinally within the same. Any form of nut and rotator whereby these functions are made possible is within the invention. Also the rotator need not be a separate shell, but provision can be made on the inside of the case for engagement with the nut.

The rotator covers the entire path of longitudinal movement of the nut, and in order to preserve the relative longitudinal positions of the shell 19 and tube 11, I prefer to make one end of the shell elastic by cutting two longitudinal slits 20 through its sides, and to turn in the edges of the shell at its outer end, so that these edges may spring into a circular groove 21 in the tube 11. This permits rotation of the shell 19 on the tube, while preventing relative longitudinal movement. Of course, instead of slitting shell 19, the same object is accomplished if shell 19 is made of two halves, which will be held together after they are in place, by a shell into which the two halves fit.

For the sake of a better appearance and finish, a tapered cover 22 is slipped over the end of the tube 11 and shell 19 so as to conceal the slitted end of the latter. Also at the inner end of the shell I prefer to fit a centering cap 23 which prevents the lead tube from rocking within the casing. Finally the outer casing 24 is slipped over the whole interior mechanism making a tight fit on the cover 22 and completing the article.

It is, of course, necessary that rotary motion should be transmitted from the casing 24 to the rotator shell 19, and I prefer to accomplish this by making the cap 23 fit over the shell 19 and into the casing 24 so tightly that, for all practical purposes, they are united into one structure. Obviously, if desired, this end may be attained by making the cover 22 fit the shell tightly.

Of course, it is understood that it is not necessary to depend upon friction to make this tight fit, but that any method can be

used which will make the cap 23, shell 19 and case 24 immovable with respect to each other. So that broadly considered, we simply have a case and a lead tube, and by revolving one with respect to the other, the pencil operates. To demonstrate the simplicity of the manufacture of this article, attention is called to the following. The lead tube is made from a piece of tubing, likewise the nut. Both can be made in large quantities on automatic machines. The lead tube, nut and pusher can be readily assembled, and these three pieces really form the important part of the pencil. When assembled, they are pushed through the rear of the rotator tube 19 until the spring-clamp at front of tube 19 engages with the circular groove 21 on the lead tube, caps 22 and 23 are now put on and the entire mechanism pushed into the case 24.

To operate the pencil it is only necessary to grasp the projecting end of the tube 11 with one hand while, with the other the casing 24 is rotated. This rotates the shell 19 which turns the nut 16, causing it to advance along the tube 11, driving the pusher 14 and lead 10 before it. If, at any time, the lead projects too far, the nut is retracted by contrary rotation of the casing, and the lead can be pushed inward by pressure on its point.

This structure may be modified in a variety of ways without departing from the

scope of my invention, and I do not limit myself to the details herein shown and described.

What I claim is—

1. A mechanical pencil comprising a threaded lead tube, a casing revolvably fitted thereon from one end of which the lead tube projects to permit it to be grasped in operation, a nut on the lead tube for feeding the lead forward and a rotator shell within the outer casing engaging said nut in a manner to permit relative longitudinal movement of the nut and shell, and having a portion engaging an annular groove in the lead tube.

2. Apparatus as in claim 1 wherein the rotator shell has a resilient slotted end whose two sides have terminal edges adapted to snap into a circular groove in the lead tube.

3. Apparatus as in claim 1 in combination with a tapered cover surrounding the lower end of the rotator shell.

4. A mechanical pencil comprising a lead tube, an outer casing, a depression on the exterior of the lead tube, and an interior shell fixed to the casing and having a turned in elastic portion engaging said depression on the lead tube so as to permit relative rotation while preventing longitudinal movement of the casing and lead tube.

In testimony whereof I have hereto set my hand on this 21st day of April 1921.

BYRON B. GOLDSMITH.
